UNITED STATES PATENT OFFICE.

HENRY S. SCHULTZ, OF EAST GREENVILLE, PENNSYLVANIA.

KNIFE.

No. 797,461.

Specification of Letters Patent.

Patented Aug. 15, 1905.

Application filed October 1, 1904. Serial No. 226,875.

To all whom it may concern:

Be it known that I, HENRY S. SCHULTZ, a citizen of the United States, residing at East Greenville, in the county of Montgomery and State of Pennsylvania, have invented new and useful Improvements in Hand Wire-Cutters, of which the following is a specification.

This invention relates to knives or wire-cutters such as are adapted to be secured to the hand of the operator.

The objects of the invention are to improve and simplify the construction of such devices.

With the foregoing and other minor objects in view, which will appear as the description proceeds, the invention resides in the precise combination and arrangement of parts and in the exact details of construction hereinafter described and claimed as a practical embodiment of the invention.

In the accompanying drawings, forming part of this specification, Figure 1 is a side elevation of a knife constructed in accordance with the invention, said knife being indicated in position upon the rear edge of the operative's hand, Fig. 2 is a section on the line 2 2 of Fig. 1. Fig. 3 is a section on the line 3 3 of Fig. 1.

Like reference-numerals indicate corresponding parts in the different views.

The improved knife comprises a blade 1, which preferably is sharpened at its outer end, as indicated by the reference-numeral 2. The blade 1 is secured to the rear edge of the operative's hand by improved means, which comprise, preferably, a stirrup 3, which is bent intermediate its ends to form a slot 4, in which is seated the rear end of the blade 1, said stirrup being secured upon the blade by means of a rivet or the like 5. Straps 6 are secured to the outer ends of the stirrup 3, said straps being adapted to be secured to each other by means of a suitable buckle 7. The stirrup 3 is adapted to embrace the wrist of the operative and to be held securely thereon by means of the straps 6. In order to avoid chafing of the wrist of the operative, the stirrup 3 is padded in any suitable manner, as indicated by 8, said padding consisting, preferably, of a ribbon or strip of flannel wrapped spirally around the stirrup.

The outer end of the blade 1 is secured in position by means of a stirrup 9, which is

formed, preferably, in two pieces clamped to opposite sides of the blade by means of a rivet, such as 10. The outer ends of the stirrup 9 are joined by a strap 11, which is secured permanently to the ends of said stirrup and is formed, preferably, of elastic material. The stirrup 9 is adapted to embrace the third and fourth fingers and to be held against displacement therefrom by means of the elastic strap 11.

In securing the improved knife in position upon the rear edge of the operative's hand the third and fourth fingers are inserted through the stirrup 9 and the straps 6 are tightened around the wrist, thus effectually preventing the disengagement of the knife from the hand.

The improved knife of this invention is effective in severing binders, and by reason of the fact that it is fastened along the rear edge of the hand it does not interfere seriously with the free movement thereof.

In its particular combination and arrangement of parts and in its exact details of construction the knife of this invention constitutes an improvement over prior devices intended for a similar purpose.

Having thus described the invention, what is claimed is—

A knife having a metallic stirrup member adapted to embrace the third and fourth fingers of the hand, said stirrup member being formed in two pieces riveted to opposite sides of the knife, an elastic strap secured to and connecting the ends of said stirrup member, a metallic stirrup member of approximately semicircular shape having a slot formed by bending the stirrup member intermediate its ends, said knife being fitted into the slot of said last-mentioned stirrup member, and said stirrup member being adapted to embrace the wrist of the hand, straps secured to the ends of said last-mentioned stirrup member, a buckle for fastening the straps, and padding upon each of said stirrup members.

In testimony whereof I affix my signature in presence of two witnesses.

HENRY S. SCHULTZ.
